J. O. MAIN.

BOX COVER.

APPLICATION FILED MAY 20, 1910.

984,282.

Patented Feb. 14, 1911.

UNITED STATES PATENT OFFICE.

JOHN O. MAIN, OF BISBEE, ARIZONA TERRITORY.

BOX-COVER.

984,282.

Specification of Letters Patent. Patented Feb. 14, 1911.

Application filed May 20, 1910. Serial No. 562,543.

To all whom it may concern:

Be it known that I, JOHN O. MAIN, citizen of the United States, residing at Bisbee, in the county of Cochise and Territory of 5 Arizona, have invented certain new and useful Improvements in Box-Covers, of which the following is a specification.

This invention relates to receptacles, having particular reference to an improved 10 cover or top adaptable particularly to spice and powder cans.

The invention has for an object to form a top of this character from a single sheet of metal, which is so bent as to carry a slide 15 adapted to regulate the opening and closing of the can.

The invention comprehends an improved cover which is provided with spaced guides and retaining lugs, which are integrally 20 formed thereon for the reception of a slide, and which carries a spring to normally and yieldably hold the slide in a closed position.

For a full understanding of the invention reference is to be had to the following 25 description and accompanying drawing, in which:

Figure 1 is a perspective view of a can having the improved cover applied thereto. Fig. 2 is a fragmentary transverse and central section taken vertically through the can, showing the slide in its normally closed position. Fig. 3 is a similar view, showing the slide in an open position. Fig. 4 is a 35 fragmentary longitudinal and central section taken vertically through the can.

Corresponding and like parts are referred to in the following description and indicated in all the views of the drawing by the same reference characters.

Referring to the drawing the numerals 40 10 and 11 designate the front and the back of a can which is provided with the sides 12 and 13. The improved cover which is positioned upon the top of the can comprises a 45 single sheet of metal 14, which is transversely crimped to form a pair of spaced ridges or guides 15 and 16 arranged midway between the ends of the cover or sheet of metal 14. The guides or ridges 15 and 50 16 are provided, adjacent their opposite ends, with inturned ears 17 which are struck from the ridges. The ears 17 are spaced upwardly from the cover 14 to accommodate a slide 18 which is snugly engaged therebelow and between the guides 15 and 16. The slide 18 comprises a sheet of metal

which is of a length somewhat shorter than the width of the cover 14, and which is provided across its outer edge with an upstanding flange 19. The inner end of the slide 60 18 is provided with a lip 20 which is turned upwardly to form a stop for engagement at its opposite ends against the adjacent ears 17. The cover 14 is provided at its opposite ends with flanges 21 and 22 to 65 seat against the inner faces of the ends 12 and 13 of the can, the flanges being soldered or otherwise secured permanently to the can. The inner side of the cover 14 is provided with an upstanding flange 70 23 to fit against the inner face of the back 11 of the can. The outside of the cover 14 carries a depending flange 24 to fit over and against the outer face of the front wall 10. The meeting ends of 75 the flanges 22 and 23 are enlarged and turned over to form a bead 25 to receive a spring 26. The spring 26 is formed from a length of suitable wire, or the like, which is arched at its outer end, as at 27, to pass 80 over the inner extremity of the guide 16, the latter determining the outer end of the bead 25. The free end of the spring 26 is looped, as at 28, to form an abutment to engage against the outer face of the lip 20. 85 The spring 26 is curved outwardly of the arched portion 27 to press against the lip 20 to hold the slide 18 normally in an outward position. The outer ears 17 form stops to engage with the flange 19 when the slide 90 90 is moved inwardly to register the opening 29 of the slide with the opening 30 formed in the central portion of the cover 14.

In the use of the can the same is inverted and the slide 18 is moved inwardly between 95 the guides 15 and 16 and beneath the ears 17 against the tension of the spring 26. The flange 19 strikes against the outer ears 17 and holds the slide to register the openings 29 and 30. The contents of the can are now 100 permitted to fall through the registered openings. To close the cover the operator releases the flange 19, when the spring 26 presses against the lip 20 and moves the slide 18 outwardly until the lip 20 strikes the inner lugs 17. When in this position the openings 29 and 30 are held out of registration with one another, and the passage through the cover is thus closed.

A can which is thus constructed can be 110 economically manufactured, and does not increase materially the proportions of the can,

so that a practical and efficient device is produced for normally closing the can, and by means of which the can may be quickly opened to discharge in small quantities the 5 contents thereof.

The openings 29 and 30 may be of any desired number to discharge the contents of the box in various quantities.

Having thus described the invention, what 10 is claimed as new is:

1. A receptacle including a hollow body, a top formed on the body and having an opening centrally therethrough, spaced guides carried upon the top, inturned ears 15 carried by the guides and adjacent their ends, a slide arranged between the guides and between the ears and having an opening therethrough for registration with the opening in the cover when the slide is moved 20 inwardly, a flange extending upwardly from the outer end of the slide to operate the same, an upturned lip formed upon the inner end of the slide, said slide and said lip adapted for engagement with the said in- 25 turned ears to limit the movement of the slide, and a spring carried by the cover and engaging at its free end against said lip to normally hold said slide in an outward position.
- 30 2. A closure including a sheet of metal having a central opening therethrough and being transversely crimped to form spaced ridges, said sheet of metal having inturned ears struck from the ridges and flanges 35 about its edges, a slide formed of a metallic plate arranged beneath the ears and between the guides and having a flange upturned

from its outer end, said slide also having an upturned lip upon its inner end, said flange and said lip adapted for engagement against said ears to limit the movement of the slide, said slide having an opening 40 formed therethrough for registration with the opening in the central portion of the sheet of metal when the slide is moved inwardly, and a spring carried by said sheet of metal for engagement against said lip to normally hold the slide in an outward 45 position.

3. A closure for a receptacle including a top for the receptacle having openings formed centrally therethrough and being crimped to provide spaced guides extending upwardly across the same, the guides having ears extending inwardly therefrom adjacent their ends and in spaced relation from the top, a slide mounted upon the top between the guides for reciprocation beneath said ears, the slide having upturned portions at its ends to limit the movement of the slide by contact with the ears, said slide also having openings formed therethrough 55 for registration at times with the openings through said top, and a spring carried by the top and engaging one end of the slide 60 to hold the same in an extended position and retain the openings out of registration.

In testimony whereof, I affix my signature in presence of two witnesses.

JOHN O. MAIN. [L. S.]
